METHOD AND APPARATUS FOR FEEDING WEBS IN FOLDERS FOR PRINTING MACHINES

Adam Howey, Brooklyn, N. Y., assignor to R. Hoe
& Co., Inc., New York, N. Y., a corporation of
New York

Application November 12, 1940, Serial No. 365,186

9 Claims. (Cl. 270—65)

This invention relates to folders for printing machines and more particularly to improvements therein to adapt them for use with printing machines wherein printed webs are collected together and fed to a folding mechanism where they are arranged and assembled into the form of product desired. In the present instance, these webs are brought together and led over a drag or forwarding roller, over a former, over web bending rollers, again brought together and fed between nipping or propelling rollers to a folding cylinder, then fed between this cylinder and a sheet cutting and collecting cylinder, past a stapling cylinder to a pair of folding rollers, and finally to a delivery fan. Under some conditions the outside web tends to separate from the others as they pass between the nipping rollers, but more often this condition tends to occur after the webs have been cut into sheets and are being folded between the folding off rollers, which cooperate with a folding blade carried by the folding cylinder. To overcome this tendency of the outside webs or sheets to separate from others as they are being collected and folded, the features and principles of this invention were devised and have been found to be particularly efficient.

One object of this invention is to provide an improved folder for a printing machine, wherein webs or sheets are collected and folded without an outside web or sheet tending to separate from the adjacent underlying ones.

Another object is to provide means in a folder for a printing machine to insure that the outside one of a plurality of collected webs or sheets will remain in its correct relationship with the others.

Still another object of this invention is to provide means to project an atomized fluid between the outside one of a plurality of webs or sheets and the feeding or folding rollers, whereby this outside web or sheet will remain in its correct cooperating relation with the other while being propelled by the rollers.

It is also an object of this invention to provide an improved folder for printing machines of generally improved construction, whereby the device will be simple, durable and inexpensive in construction, as well as convenient, practical, serviceable and efficient in use.

With the foregoing and other objects in view, which will appear as the description proceeds, the invention resides in the combination herein-after described and claimed.

The preferred embodiment of the invention is

illustrated in the accompanying drawings, wherein:

Figure 1 is a somewhat diagrammatical view of a printing machine embodying the features and principles of this invention; and

Figure 2 is a similar view of the folder shown in Figure 1, looking in the direction of arrow 2.

Referring now to the drawings, wherein like reference numerals designate like parts throughout the several views, the numeral 11 denotes generally one printing unit of a printing machine such as is well known in the printing field. Such a printing unit includes two pairs of plate and impression cylinders 12 and 13 respectively, ink distributing cylinders 14 with cooperating ink transfer rollers 15 and 16, ink distributing rollers 18 and 19, and suitable web guiding rollers 21, 22 and 23. A plurality of such printing units are usually provided in a printing machine, and a plurality of webs 24, each leading from a different printing unit, are brought together into superimposed relation at the delivery end of the machine, where they are passed over a drag roller 25 and onto a former 26.

By means of the former 26, and of web bending rollers 27 and 28, the collected webs are again superimposed upon each other and led between cooperating and driven nipping or propelling rollers 29, 31 and 34, 35. It is the usual practice to drive the nipping rollers 29, 31 and 34, 35 slightly faster than the normal speed of other rollers and the cylinders of the printing machine so as to exert a slight pull upon the collected webs, and this has been found to cause the outside web 32 to be slightly separated from those underneath, due probably to its direct engagement with the cooperating rollers 29, 31, and 34, 35. To offset this tendency, it is proposed, as one feature of this invention, to provide means to project a spray of atomized fluid, such as an emulsion of oil and water, between this outer web 32 and, for instance, the roller 31. The emulsion of oil and water is supplied from a source of supply (not shown) under pressure to an atomizer nozzle 33, whereby it is directed between the outer web 32 and the periphery of the roller 31, and any others desired. Application of an atomized fluid, as above described, has been found to obviate the tendency for the outermost web to separate from the others, whereby all of the webs may be caused to pass between the rollers 29, 31, and 34, 35 in correct alignment.

After passing between the rollers 29, 31 and 34, 35, the collected webs 24 are passed to cooperating sheet folding, sheet cutting and collecting

cylinders 36 and 37 respectively. The sheet cutting and collecting cylinder 37 is provided with the usual cutting blade 38 and collecting pins 39. By means of the sheet collecting pins 39, sheets cut from the webs 24 may be collected and later transferred to similar sheet collecting pins 41 provided on the folding cylinder 36, which has suitable blocks 42 to cooperate with the cutting blade 38 on the cylinder 37.

The folding cylinder 36 is provided with folding blades 43 which cooperate, in timed relation, with the delivery of collected sheets from the collecting cylinder 37 and the cylinder 36, with a pair of folding-off rollers 44 and 45 to fold these sheets. The rollers 44 and 45 fold the plurality of collected sheets 46 and direct them into a delivery fan 47. In this instance, a stapling cylinder 48 is provided which has a stapling plunger 49 adapted to cooperate with anvils 51, on the folding cylinder 36, to staple the collected sheets together as they pass between the stapling cylinder 48 and the folding cylinder 36.

It has been found that the outer sheet 52, of the plurality of sheets on the cylinder 36, under some conditions tends to separate from the others, and, therefore, means has been devised, as one feature of this invention, to obviate this tendency. The means for obviating the above referred to tendency of the outer sheet 52 to separate from the others, includes the provision of means to project a spray of atomized fluid, preferably an emulsion of oil and water, between this outer sheet and one of the rollers 44 or 45. Preferably, the atomized fluid is projected from an atomizing nozzle 53 which is connected, as by a pipe 54, to a source not shown of such fluid under pressure. The nozzle 53 projects this fluid between the roller 44 and the portion of the outer sheet 52 which has passed beyond or forward of the folding point, because it is at this point that most of the separation takes place, due probably to the fact that the upper surface of the roller 44 moves in a direction opposite to that of the adjacent surface of the cylinder 36 and travel of the sheets thereon.

In some instances, it is desirable to provide both of the above referred to atomized fluid projecting means, but, under some conditions, the one located at the roller 31 may be omitted, although its use occasionally is desired, as the emulsion-sprayed web portion becomes the outer sheet at the folding-off rollers 44 and 45, and the emulsion thereon adds to the effect produced by that projected from the nozzle 53. In instances where the sheets are stapled, as by the means disclosed, the provision of means to project atomized fluid at the folding roller 44 is especially advantageous because it prevents the outer sheet separating from the others, for if such separation occurs this outer sheet may be torn from the staple and thus damage the product being delivered.

It will be understood that the invention may be embodied in other specific forms without departing from the spirit and essential attributes thereof, and it is therefore desired that the present embodiment be considered in all respects as illustrative and not restrictive.

What I claim is:

1. In a folder for a web printing machine, a former propelling means for printed webs leading from the machine and over the former, the propelling means including cooperating rollers, means exterior of the cooperating rollers to project atomized lubricating fluid between one of the rollers and the web directly engaged thereby, a folding cylinder having a folding blade, a web

cutting and sheet collecting cylinder cooperating with said folding cylinder to cut and collect sheets from the web, a sheet stapling cylinder cooperating with the folding cylinder to staple sheets cut from the web, cooperating folding rollers arranged to cooperate with the folding blade on the folding cylinder to fold the stapled sheets, and means exterior of the folding rollers to project atomized lubricating fluid between one of the folding rollers and the leading portion of the outside sheet of the product, to prevent its separation from the inside sheets.

2. The method of feeding a plurality of webs in multi-ply relation through a printing or folding machine, which includes engaging the outermost web with a web-propelling roller operating at a higher peripheral speed than the linear speed of the web and applying a film of lubricating emulsion against the periphery of the roller and outermost web in sufficient quantity to lubricate the web-propelling surface of the roller and to alter the frictional characteristics of the outermost web to prevent the frictional engagement between the web-propelling surface of the roller and the outermost web from separating the outermost web.

3. The method of feeding a plurality of webs in multi-ply relation through a printing or folding machine, which includes engaging an outermost web with a driven web-propelling roller and spraying lubricating emulsion between the roller and the outermost web to lubricate the web-propelling surface of the roller and to alter the frictional characteristics of the outermost web to prevent the frictional engagement between the web-propelling surface of the roller and the outermost web from separating the outermost web from the next outermost web.

4. The method of feeding a plurality of webs in multi-ply relation through a printing or folding machine, which includes engaging an outermost web with a driven web-propelling roller and spraying atomized lubricating emulsion between the roller and the outermost web to lubricate the web-propelling surface of the roller and to alter the frictional characteristics of the outermost web to prevent the frictional engagement between the web-propelling surface of the roller and the outermost web from separating the outermost web.

5. The method of feeding a plurality of webs in multi-ply relation through a printing or folding machine, which includes engaging an outermost web with a driven web-propelling roller operating at a higher peripheral speed than the linear speed of the web and spraying atomized lubricating emulsion between the roller and the outermost web to lubricate the web-propelling surface of the roller and to alter the frictional characteristics of the outermost web to prevent the frictional engagement between the web-propelling surface of the roller and the outermost web from separating the outermost web from the next outermost web.

6. In a folder for a printing machine adapted to produce a product composed of a plurality of printed superimposed webs, the combination with cooperating web-propelling rollers operably engaging the outermost webs of means exterior of the web-propelling rollers to project lubricating emulsion between one of the rollers and an outermost web to lubricate the web-propelling surface of the roller and to alter the frictional characteristics of the outermost web to prevent the

frictional engagement between the web-propelling surface of the roller and the outermost web from separating the outermost web from the next outermost web.

7. In a folder for a printing machine adapted to produce folded multi-ply products, the combination with a folding cylinder having a folding blade and cooperating folding rollers arranged to cooperate with the folding blade to fold the product, of means arranged to project lubricating emulsion from a point exterior of the folding rollers between an outermost ply of each product and a folding roller to lubricate the web-propelling surface of the roller and to alter the frictional characteristics of the outermost ply to prevent the frictional engagement between the web-propelling surface of the roller and the outermost ply from separating the outermost ply from the next outermost ply of the product.

8. In a folder for a printing machine to produce a product composed of a plurality of superimposed webs and the combination with cooperating web-propelling rollers located to engage the outermost webs to thereby propel the webs, a folding cylinder and a cutting cylinder having cooperating means to cut the webs into sheets and superimpose the sheets, a folding blade operably supported by the folding cylinder, folding rollers arranged to cooperate with the folding

blade to fold the sheets into a product, of means exterior of the said web-propelling rollers to project lubricating emulsion between a web-propelling roller and an outermost web, and means exterior of the folding rollers for projecting lubricating emulsion between a folding roller and an outermost sheet, the emulsion serving to lubricate the rollers and to alter the frictional characteristics of the outermost webs or sheets to prevent the frictional engagement of the roller against the web or sheet from separating the outermost web or sheet.

9. In a folder for a web printing machine, the combination with propelling means for printed webs being led from the machine, a folding cylinder having a folding blade, a web cutting and sheet collecting cylinder cooperating with said folding cylinder to cut and collect sheets from the webs, a sheet stapling cylinder cooperating with the folding cylinder to staple the sheets cut from the webs and cooperating folding rollers arranged to cooperate with the folding blade to fold the stapled sheets, of means exterior of the folding rollers to project lubricating emulsion between a folding roller and the sheet engaged thereby to reduce the friction between the roller and the sheet.

ADAM HOWEY.
